UNITED STATES PATENT OFFICE.

JAMES F. WHELAN, OF PHILADELPHIA, PENNSYLVANIA.

DESIGN FOR A PORTABLE ELECTRIC LAMP.

Application filed November 12, 1927. Serial No. 24,095. Term of patent 14 years.

To all whom it may concern:

Be it known that I, JAMES F. WHELAN, a citizen of the United States, residing at Philadelphia, in the county of Philadelphia and State of Pennsylvania, have invented a new, original, and ornamental Design for a Portable Electric Lamp, of which the following is a specification, reference being had to the accompanying drawing, forming a part thereof:

Fig. 1, is a plan view of a portable electric lamp showing my new design.

Fig. 2, is a side elevation thereof.

Fig. 3, is also a side elevation at right angles to the showing of Fig. 2.

I claim:

The ornamental design for a portable electric lamp as shown.

JAMES F. WHELAN.
